THERMOMETER CASE

Donald A. Draudt, Lorain County, Ohio, assignor to Clin-Aid Products, Inc., Cleveland, Ohio, a corporation of Ohio

Filed June 2, 1967, Ser. No. 7,345

Term of patent 14 years

(Cl. D52—7)

FIG. 1

FIG. 3

The broken line portions in FIG. 3 are shown for purposes of illustration only.

I claim:

The ornamental design for a thermometer case, as shown and described.
